UNITED STATES PATENT OFFICE.

EDWARD L. WAYBRANT, OF NEW BEDFORD, MASSACHUSETTS.

MEANS FOR DISTRIBUTING EXPLOSIVE MIXTURES TO INTERNAL-COMBUSTION ENGINES.

Application filed September 15, 1925. Serial No. 56,417.

This invention relates to the distribution of explosive fuel charges into the explosion chambers or cylinders of internal combustion engines, and more particularly engines utilizing explosive charges of gasoline or other equivalent fuel, which are drawn into the various cylinders during the suction or intake stroke of the pistons from a carburetor, and ignited or exploded in the cylinder by electric sparks. These sparks are produced at the inner ends of spark plugs which are inserted in the various cylinders through suitable openings formed in the cylinder head or cylinder block.

In the usual types of spark plugs employed in automobile or other internal combustion engines, there is present an annular internal pocket at its inner end, between the bushing which carries one of the sparking electrodes and which is adapted to be screwed into openings formed in the cylinder head or cylinder block and the dielectric member which is centrally mounted therein and provided with the other sparking electrode.

Thus, when an explosion has occurred in the cylinder, there is a tendency for burned gas to become entrapped in such pocket, and for some of such entrapped gas to remain in the pocket even after a fresh fuel charge has been introduced into the cylinder. Moreover, any oil which might work its way past the piston rings and be deposited in the pocket within the plug tends to carbonize and become deposited as carbon on the plug and on the ignition points of the electrodes.

Hence, the object of this invention, broadly stated is to provide a method of and means for removing the foul gases from the pocket as well as to decrease the liability of deposition of carbon on the electrodes in a spark plug of the type indicated.

In the practice of the present invention, this object is attained by sweeping out the burned gases from within the spark plugs and replacing or supplanting them with fresh explosive charges drawn therethrough from the carburetor of the engine. Thus a perfect ignition charge is ensured at the points of ignition of the electrodes when ignition is to be effected so that a properly timed and positive ignition and explosion of the explosive mixtures in the cylinders is realized, together with the consequent development of more power by the engine.

Moreover, the fresh charge of fuel tends

to blow or "wash off" any carbon or oil deposited on the electrodes or in the spark plug, as well as to cool the plug, which makes for exceptionally long life as well as efficient service during operation. This is all accomplished while supplying the cylinders with explosive charges, as usual through intake valves from the intake manifold. In other words, a portion of the explosive charge drawn into the intake manifold is diverted to a second manifold or reservoir from which it is supplied and distributed through suitable tubes and valves into each of the spark plugs. Thus, while no more explosive mixture or fuel is used or required than ordinarily, the charge is distributed in a more efficient manner, thus increasing the efficiency of the engine. The necessity for cleaning or replacing spark plugs is by this means greatly reduced. The distribution is merely one of delivering the large portion of explosive charge through the intake valve, as ordinarily, and the remaining portion directly into the interior of the spark plug.

With these and other features and objects in view, the invention consists in the method of distributing explosive charges and the construction, combination, and arrangement of parts employed in connection therewith, as will be more fully hereinafter described in conjunction with the accompanying drawings, in which

Figure 1 illustrates in side elevation a portion of an engine equipped with an arrangement or device for diverting and distributing a portion of the charge from the intake manifold into each of the spark plugs.

Figure 2 represents a detail section through a cylinder, on the line 2—2 of Figure 1, and shows in end elevation the device as employed in connection with a cylinder.

Figure 3 represents a detailed section through a plug installed in a cylinder, and also illustrates in sectional view a portion of the device used in connection with each plug.

Referring to Figure 1 of the drawings, 1 indicates in general a 4-cylinder engine equipped with an arrangement or device for supplying the combustible mixture into the housing of each spark plug. Of course, any engine in which spark plugs are used, and consisting of any number of cylinders, may be provided or afforded with the present improvement, the particular engine chosen being by the way of illustration only. The

engine consists of the usual cylinder block 2, provided with the cylinder head 3, having suitable openings therein through which spark plugs indicated as a whole at 5 are inserted into each cylinder. The cylinder walls of the engine are externally cooled, as by surrounding them with the usual water jacket supplied with water circulated through the conduit 6 from the radiator, and the cylinders communicate, by means of the usual exhaust valves (not shown) and the exhaust pipe 7, with the exhaust manifold 8, from which the exhaust gases are expelled or discharged.

15 During the suction stroke of the piston 14 of each cylinder, the intake valve 15, which is actuated by a cam 16 on the cam shaft 17, is lifted from its seat, opening the intake port 18, through which a properly mixed 20 fuel charge is supplied to the cylinder 19 from the branches 9 connected with the usual intake manifold 10, which communicates with a carburetor of any suitable type, indicated as a whole at 11, and to which gasoline or other fuel is delivered from the fuel supply or storage tank by a tube 12. The fuel is vaporized in the carburetor and mixed with a suitable proportion of air to 25 form a proper explosive mixture to be introduced and exploded in the cylinders. Thus far, I have briefly described an engine of a usual type, and a well known method 30 of distributing explosive charges into the cylinders thereof.

35 The spark plug 5 shown comprises the bushing or shell 31, which is adapted to be screwed into a suitable threaded opening formed in the cylinder head or block of the engine for insertion into a cylinder. The bushing is internally flanged, and is provided with a dielectric member 50, made of porcelain, for example, which is provided with a shoulder adapted to seat on the flange of the bushing. The dielectric member 50 is 40 provided with a sparking electrode 53 extending axially therethrough, and to which current is supplied at properly timed intervals from a feed wire 54 fastened thereto by the nut 55, screwed on to the upper end of the electrode. The spark is completed by a second sparking electrode 57, mounted on the bushing 31, which is grounded through the engine and projects laterally toward the electrode 53, leaving a sparking gap therebetween. The dielectric member is held in 45 position and against the bushing 31 by a gland nut 60 screwed into the bushing 31, and which when tightened forces the dielectric into close or tight contact at the flange 50 provided by the bushing. The dielectric member 50 is of diminishing taper toward its lower end, and is spaced from the inner wall of the shell 31, thus forming an internal pocket or compartment 52. Of 55 course, any other suitably constructed spark

plug may be employed, wherein an interior pocket or compartment is afforded.

In accordance with the present invention on the suction or intake stroke of the piston, provision is made to establish communication between the interior pocket or compartment 52 in each spark plug 5 directly above the sparking points of the electrodes, and the explosive mixture formed in the carburetor and supplied to the intake manifold. To this end, a hole is tapped in the intake manifold to form an outlet for a portion of the explosive mixture, so that part of it may be drawn into a distributing system constructed and arranged to introduce the explosive mixture into each spark plug.

80 The distributing system comprises a tube 20, which is threaded at one end and screwed into the tapping formed in the intake manifold and is connected at its other end to a second manifold or distributing reservoir 21, from which explosive charges are separately drawn into each spark plug during the suction or intake strokes of the corresponding piston. The tube 20 is preferably provided with a valve 22, by means of which the portion of the charge diverted from the manifold 10 may be accurately regulated and controlled, and also a spiral trap 23 to 85 permit an accumulation of condensate of the explosive fuel on stoppage of the engine. Upon again starting the engine, the fuel condensate in the trap 23 is sucked through the spark plugs and into the cylinders so that a convenient priming charge is available for the easy starting of the engine. This initial priming charge is especially desirable when the engine is cold.

90 The diverted charge is supplied on the intake or suction stroke of each cylinder, from the distributing reservoir 21 through a tube 28 and thence through a ball check valve indicated at 29, from which it is conducted through a tube 30 opening and extending into the bushing or shell 31 which covers the outer electrode 57. The charge is thus introduced directly above the sparking points acting to scavenge the recess or pocket 52 of burned gas, some of the fuel flowing or 95 sweeping between the points. The explosion of the combustible or explosive mixture in the pocket tends to project or throw the burning gases outwardly into the cylinder, thus increasing the rate or speed of propagation of combustion through the combustible mixture in the cylinder.

100 To allow the removal of the spark plug from the engine when desired, but without disturbing the tight joint or connection made with the tube 30, the tube 28 is 105 detachably joined on to the valve 29, so that the spark plug 5, the valve 29, and the tube 30 connecting both may be removed from the engine as a unit. For this purpose, as 110

shown, the end of the tube 28 is provided with a tapered nipple or fitting 34, seated tightly in a socket 35 formed at the lower portion of the valve. The joint thus provided is maintained tight by a gland nut 36 slipped over the tube 28 and screwed on to the housing 38 of the valve, so that when the nut is tightened, the tapered surface of the fitting 34 is forced into close contact with the surface of the socket 35.

5 The channel in the tube 28 continues unobstructed through the fitting 34 and the housing 38, wherein it is normally obstructed by a ball 40 resting on a seat formed in 15 the housing. On the suction stroke of the piston, however, the ball 40 is lifted from its seat, thus opening the channel in the housing and allowing the explosive charge to be drawn through the tube 30 and into the 20 spark plug. The ball may be held to its seat by a light spring 42 reacting between it and the housing cap 43 screwed on to the upper end of the housing.

While the description of the means employed for distributing the explosive mixture has been limited to what may be considered a preferred embodiment, it is of course understood that any other suitable system or arrangement may be employed, if 25 desired. In any event, however, the essential feature lies in diverting a portion of the properly mixed explosive charge formed in the carburetor into the interior of the spark plugs, while supplying the corresponding cylinders with explosive charges, as 30 usual, through the inlet valves.

I am well aware of the fact that it has been proposed to prime an engine only upon starting by causing a delivery of raw 40 liquid fuel into the cylinders from a suitable outside source through the spark plugs. In the present invention, however, while priming may be effected, the salient feature resides in conducting an explosive or carbureted mixture from the carburetor into the 45 interior of each spark plug during each suction stroke of the corresponding piston. Thus the burned or exhaust gas is swept out and a clean mixture is ensured at the spark- 50 ing points of the spark plugs during ignition so as to produce an instantaneous combustion and a development of more power

and without the necessity of additional fuel from an outside source. Moreover, the spark plugs are maintained clean and efficient in 55 operation and their life is prolonged.

Having thus described this invention, it is evident that various changes may be resorted to in procedure, as well as in form, construction, and arrangement of the parts, 60 without departing from the spirit or scope of my invention. Hence I do not wish to limit myself strictly to the structure herein set forth, but

What I claim is:

1. The combination with the spark plugs of an internal combustion engine, of apparatus for diverting a portion of the explosive mixture formed in the carburetor thereinto, which includes a tube leading from the intake manifold of the engine, a trap in said tube permitting an accumulation of condensate of the explosive fuel on stoppage of the engine, a reservoir communicating with said manifold by said tube, and a plurality 70 of tubes leading from said reservoir, each of which tubes communicates with the interior of a spark plug and is provided with a check valve permitting explosive mixture to be admitted into the spark plug only on the 80 intake stroke of the corresponding piston.

2. The combination with the spark plugs of an internal combustion engine, of apparatus for diverting a portion of the explosive mixture formed in the carburetor thereinto, which includes a tube leading from the intake manifold of the engine, a valve in said tube by means of which the portion of the charge diverted through said tube may be controlled in amount, a trap in said tube 90 permitting an accumulation of condensate of the explosive fuel on stoppage of the engine, a reservoir communicating with said manifold by said tube, and a plurality of 95 said tubes leading from said reservoir, each of which tubes communicates with the interior of a spark plug and is provided with a check valve permitting explosive mixture to be admitted into the spark plug only on the 100 intake stroke of the corresponding piston.

In testimony whereof I have affixed my signature.

EDWARD L. WAYBRANT.
